UNITED STATES PATENT OFFICE.

A. BRINTON KURTZ, OF CINCINNATI, OHIO, ASSIGNOR OF ONE-HALF TO
FREEMAN C. LUDLOW, OF SAME PLACE.

MECHANICAL TELEPHONE.

SPECIFICATION forming part of Letters Patent No. 298,479, dated May 13, 1884.

Application filed May 10, 1883. (No model.)

To all whom it may concern:

Be it known that I, A. BRINTON KURTZ, of the city of Cincinnati, in the county of Hamilton and State of Ohio, have invented certain new and useful Improvements in Mechanical Telephones, of which the following is a specification.

My invention relates that class of instruments known as "mechanical telephones," and the objects and advantages of my invention will be apparent from the drawings and the following description.

Referring to the drawings forming part of this specification, Figure 1 is a front elevation of my invention. Fig. 2 is a side elevation of the same. Fig. 3 is a vertical central section taken at the line xx of Fig. 1, showing the position of the parts when the instrument is in a condition to transmit a message. Fig. 4 is a sectional elevation taken at the same point as Fig. 3, but showing the position occupied by the various parts for ringing the bell of the instrument at the opposite end of the telephonic line. Figs. 5 and 6 are enlarged views of parts of the bell-ringing mechanism.

A is the box or frame of the instrument, which is secured to a suitable back, as A'.

To the back A', within the box and near its top, is secured one edge of a piece, B, extending nearly to the front of the box A, and being preferably a slight distance below its top, for the purposes hereinafter mentioned, and to the front edge of this piece B is secured one end of the diaphragm C. This diaphragm extends nearly to the bottom of the box or frame and from side to side, not, however, coming quite in contact with the sides of the box or frame, so that the diaphragm is everywhere out of contact with the box or frame, and is in contact with piece B alone, the lower end of the diaphragm being thus free to vibrate. The front surface of the diaphragm C is slightly removed from the front of the box, leaving a chamber, a, between the diaphragm and the box. Opposite the free end of the diaphragm is the speaking orifice or tube b, which passes through the front of the box. The wire C' is suitably connected to the free end of the diaphragm, and when so connected any vibrations imparted to the diaphragm by a person talking in front of the opening b will

be imparted to the wire C'. The diaphragm being free at all points, excepting at one edge, is much more susceptible to vibrations than a diaphragm supported around its entire periphery, (as is the case in the telephones heretofore constructed,) and my diaphragm will receive and transmit a very clear and distinct sound. The amount of vibration permitted to the diaphragm C will be still more increased when the piece B is supported substantially as follows: The piece B is preferably free, except at its back edge, which is secured to the back A', and thus allows a very free vibration of the diaphragm.

It is desirable to provide means for ringing a bell at either end of the line, by which the person at one end can call the attention of the person at the other end of the line, and for this purpose I employ suitable mechanism, a preferred form of such mechanism being shown in the drawings, and which is as follows: A lever, D, is hinged or pivoted to the under side of the piece B, the free end of which lever passes through an opening, a', in the bottom of the box, and is provided with a suitable handle, D', by which the free end of the lever may be moved forward or backward. The preferable method of pivoting the lever D to the piece B is by forming a T-head, d, on the end of the said lever, which head engages with staples d', driven into the piece B at either side of the lever. This construction allows a perfect freedom of motion of the free end of the lever. The wire C' is to be connected to the diaphragm, preferably by a connection whereby the wire can be readily connected to and disconnected from the diaphragm at will. A desirable form of connection is as follows: The wire C' is connected to the diaphragm by means of a hook, E, and an eye, E', the latter being secured to the diaphragm, the hook being so shaped that it may be readily disconnected from the eye.

A desirable means for enabling the hook E to be connected to or to be disengaged from the eye E' is as follows: The rear end of the hook to which the wire C' is connected is provided with a cross-bar, e, extending laterally. The rear face of this cross-bar is preferably flat, as shown in Figs. 3 and 4. In the front face of the lever D is formed a recess, e', which

recess is large enough to receive the cross-bar *e* of the hook and allow a slight rocking of the bar therein, no longitudinal motion of the bar being permitted. The bottom of this recess is made flat, so that when the bar *e* is in the recess, its flat face resting against the bottom of the recess, the hook *E* will be retained at the desired angle to the lever *D*. The wire *C* passes through an opening, *e'*, formed in 10 the lever *D*. Behind the lever *D* is placed a spring, *F*, either spiral, as shown, or of any other desired form, having a tendency to press the free end of the lever forward toward the diaphragm. A rod or shaft, *F'*, passes transversely through the box in front of the lever *D*, one end of said shaft being provided with a crank, *f*, having a handle, *f'*, of suitable weight. At the point on the shaft *F'* which is opposite the lever *D* is formed a bend or crank, *G*, 15 which, when the shaft is turned, comes in contact with the front face of the lever, and this crank *G*, in connection with the spring *F*, causes the lever *D* to move back and forth when the shaft *F'* is turned. The front face 20 of the lever *D* at the point against which the crank *G* strikes is preferably slightly concave, as shown. To the side of the box *A* which is opposite the crank *f* are connected the bells *H*, and to that end of the shaft *F'* which is at 25 this side of the box is pivoted the clapper-rod *H'*, to the end of which is connected a head or hammer, *h*, adapted to strike against the bells *H*. The connection between the shaft *F'* and the clapper-rod *H'* is made by a knife-30 blade joint, *h'*, which joint enables the clapper-rod *H'* to be placed at right angles to the shaft, as shown in Fig. 5, or straightened out, so that it will lie in a line with said shaft, as indicated by dotted lines in said figure. When 35 the clapper-rod *H'* is turned up at right angles to the shaft *F'*, the hammer *h* lies between the bells *H*, as shown in Fig. 2.

As above described, the operation of my invention is as follows: Suppose the telephone 40 to be at rest—that is, in the condition in which it will be when no message is being transmitted—the various parts will then be in the position shown in Figs. 2 and 4. The hook *E* will be disengaged from the eye *E'*, and the 45 bar *e* resting in the recess *e'* in the lever *D*, and the tension of the wire *C* is then received by the lever *D*, which will thus be drawn toward the back *A'* and rest against the spring *F*, which forms a cushion. When the lever *D* 50 is in this position, the weighted handle *f'* of the crank *f* hangs in the position indicated by dotted lines in Fig. 4, and this turns the shaft so that the crank *G* will lie in contact with the lever *D*. The clapper-rod *H'* being now turned 55 up at right angles to the shaft *F'*, the hammer *h* lies between the bells *H*, as shown in Fig. 2. When it is desired to call the person at the opposite end of the line, the person desiring to make the call first turns the clapper-60 rod *H'* down, so that it will be disengaged from the bells, and then turns the crank *f,f'*, and the crank *G* in the center of the shaft, by

striking against the lever *D* as the shaft *F'* is turned, moves this lever, which causes the wire *C* to reciprocate, and these reciprocations are 70 transmitted to the lever *D* of the instrument at the opposite end of the line, and the movement of this lever, by acting on the crank *G* of the shaft *F'*, moves this shaft, which in turn moves the clapper-rod *H'* and hammer *h*, and 75 the hammer is thus caused to strike the bells *H*. As soon as the person making the call has turned the crank of his instrument, he again turns the clapper-rod up, and the person answering the call turns the clapper-rod 80 of his instrument down, and answers the call in the same manner that the call was made. The party at each end of the line now takes hold of the handle *D'* of the lever *D* and moves it forward, which brings the end of the hook 85 *E* in contact with the eye *E'*, and the end of the hook rises over the eye and drops into it, after the manner of a latch. When the hook has thus been engaged with the eye, the operator releases his hold on the handle *D'*, and 90 the lever *D* then drops away from the cross-bar *e*, and occupies the position shown in Fig. 3, and the wire is now connected to the diaphragm, and any vibrations of the diaphragm will be transmitted to the wire. When the 95 parties have finished talking, the handle *D'* is again brought forward until the tension of the wire is taken up by the lever *D*, and the hook *E* is lifted and disengaged from the eye *E'*, when the various parts will again assume 100 the position shown in Figs. 2 and 4. In the present instance, the hook is lifted or disengaged by the thumb or finger of the hand of the operator which is grasping the handle *D'*.

It will be observed that my invention 105 enables the diaphragm to be relieved of the strain of the transmitting-wire *C*, except when the telephone is in use, and that when the diaphragm is connected to said wire the operator has both of his hands free for writing down the message or for other proper work. If for any reason it becomes desirable to change the call-signal, that part of the apparatus shown which relates to the ringing of the bell will be altered, or altogether dispensed 115 with, according to the mode of call adopted.

The diaphragm *C* may be many-sided, or oval, or circular, when preferred, instead of four-sided, as shown. As suggested in the opening of my specification, the box *A* may, 120 when desired, be a frame-work. I prefer, however, to use a box substantially as shown.

The principal features of my invention are, first, the diaphragm attached and located substantially as before set forth; second, the means for connecting the diaphragm to the transmitting-wire and for disconnecting the diaphragm therefrom; third, the mode or means for making the call-signal.

While the several features of my invention 130 are preferably used together, one or more may be employed without the remainder, and so far as applicable one or more of said features may be employed in connection with tele-

phonic devices other than that herein particularly specified.

Having thus described my invention and its mode of operation, what I claim as new, 5 and desire to secure by Letters Patent, is as follows:

1. In a telephone, a diaphragm connected at or near one portion only of its edge to a support, as B, the remaining portion being free 10 to vibrate, and a transmitting-wire adapted to be connected to said diaphragm at some point between its free edge and its point of connection, and to be disconnected therefrom at will, substantially as and for the purposes 15 specified.

2. The diaphragm C, connected substantially as described, and provided with an eye or staple, E', in combination with the wire C', connected to a hook, E, said hook having a 20 cross-bar, e, and a lever, D, hinged or pivoted at its upper end, said lever being adapted to engage with the cross-bar e, by which the hook E may be drawn forward to engage the eye E', substantially as and for the purposes specified. 25

3. The lever D, pivoted at its upper end, and provided with a cup or recess, e', in combination with the wire C', passing through said lever, and connected to a cross-bar, e, in 30 front of the lever, said cross-bar being adapted to rest in the cup or recess e', and having the hook E, adapted to engage the eye of a diaphragm, substantially as and for the purposes specified.

35 4. The lever D, pivoted at its upper end,

and suitably connected near its lower end to the wire C', in combination with the shaft F', passing through the box A from side to side, and provided with a crank, G, adapted to engage the lever D, said shaft being provided 40 with a suitable crank for causing it to rotate, and a spring, F, placed behind the lever, substantially as and for the purposes specified.

5. The lever D, pivoted at its upper end, and connected near its lower end to the wire 45 C', in combination with the shaft F', having a crank or bend, G, to engage with said lever, one end of said shaft being provided with a crank, f, having a handle, f', and the other end being provided with a clapper-rod and 50 hammer for ringing the bell, substantially as and for the purposes specified.

6. The shaft F', being provided at one end with a crank, f f', and at the other end with a clapper-rod, H', having a hammer, h, the clapper-rod being connected to the shaft F' by a knife-blade joint, h', to permit said rod to be turned at right angles to the shaft, or in a line therewith, in combination with the bells H, 55 substantially as and for the purposes specified. 6c

7. In combination with a diaphragm suitably supported and provided with an eye or staple, E', the transmitting-wire provided with hook E, and mechanism for causing the hook to engage with said eye, substantially as 60 and for the purposes specified.

A. BRINTON KURTZ.
